UNITED STATES PATENT OFFICE.

EDWIN LUNDGREN, OF FREDERICK, MARYLAND, ASSIGNOR TO COMBUSTION ENGINEERING CORPORATION, OF NEW YORK, N. Y., A CORPORATION OF NEW YORK.

UNDERFEED-STOKER TUYÈRE.

Application filed November 28, 1923. Serial No. 677,503.

My invention relates to tuyère structures that are particularly adapted for use with stokers of the inclined underfeed type.

An object of the invention is to provide a tuyère structure of this character with the use of which the most efficient and economical burning of the fuel may be obtained.

Another object of the invention is to provide a tuyère structure of this character which is better adapted to withstand the heat of the furnace, and is otherwise more durable than those heretofore provided, resulting in decreased maintenance cost and shut downs for repairs.

Another object of the invention is to provide a tuyère of the character indicated having outlet channels through which the air is guided in such a manner that it is delivered to the fuel without sudden shock.

The several features of the invention whereby the above mentioned and other objects may be obtained will be clearly understood from the following description and accompanying drawing, in which,

Figure 1 is a side elevation, partly in section, of a tuyère structure embodying the features of the invention in their preferred form, the tuyère structure being shown as mounted upon the wall of the retort, the retort wall being shown by broken lines;

Fig. 2 is a top plan view of one of the tuyères shown in Fig. 1;

Fig. 3 is a bottom plan view of the same; and

Figs. 4, 5 and 6 are sectional views taken on the lines 4—4, 5—5, and 6—6 of Fig. 3, respectively.

The terms "front" and "rear" as employed herein in describing the tuyère structures, refer to the left and right hand ends thereof, respectively, viewing Figs. 1, 2, and 3 of the drawings.

The stoker tuyère illustrated in the drawings comprises a plate 2 having the forward portion 4 of its longitudinal sides substantially parallel and the rear portion 6 of its longitudinal sides inclined inwardly toward its rear end, the rear end of the tuyère being rounded. The under side of the plate 2 is provided with a depending rib 8 extending along the margin of the longitudinal sides and rear end thereof, the forward end portions 10 of the rib being inclined upwardly and forwardly to the top surface of the plate. The tuyère plate is further provided

with a central opening 12 having a reduced rear end portion 14, and the under side of the plate is provided with a depending hook-shaped lug 16 spaced between the rear end wall of the opening 12 and the rear end of the plate, and with lugs 18 arranged adjacent its forward end.

The tuyères are arranged one upon the other with the rear end of each tuyère projecting a distance beyond the adjacent overlying tuyère, the inclined end portions 10 of the rib 8 resting upon the retort walls which are indicated by broken lines at 20. The tuyères are held in position on the retort walls by the engagement of the lugs 18 with suitably arranged sockets in the walls and the tuyères are held down upon each other by means of the lugs 16, each of which extends through the rear end of the opening in the adjacent underlying tuyère and hooks under the rear end wall of the opening.

In the illustrated construction the inner marginal portion 22 of the rib 8 is transversely inclined upwardly and inwardly to the under side of the body of the plate. The rear end portion of the under side of the rib 8 is provided with a plurality of relatively narrow radially extending channels forming alternately arranged air passages 24 and vanes 26. The longitudinal portions of the ribs 8 are provided with a plurality of relatively narrow channels that open out through the sides of the tuyères and each is curved inwardly and forwardly therefrom, the channels forming alternately arranged air passages 28 and vanes 30 of substantially the same width.

With this construction it will be apparent that the air admitted to the under side of each tuyère will pass out through the air passages 24 and 28, and that as these air passages and vanes, particularly the curved passages 28 and vanes 30, are of considerable length, a large cooling surface for the air is provided, and the air will pass therethrough to the fuel without sudden shock.

As the air passages and vanes are located adjacent the longitudinal edge of the rear portion of the tuyère, which is where the tuyère casting is most affected by the heat of the furnace, the large cooling surface provided tends to prevent overheating of this portion of the tuyère.

In order to still further increase the life of the tuyère casting the rear end portion of

each tuyère projecting beyond the adjacent overlying tuyère and which is exposed to the incandescent fuel bed, is raised at 32 a distance above the top surface of the body of the tuyère so as to give a greater thickness of metal than otherwise available and thus give greater wear against corrosion of the metal, the rear portion of the top surface of the raised portion 32 being inclined downwardly and rearwardly to the end of the tuyère so as to provide an effective fuel supporting surface.

As will be evident to those skilled in the art my invention permits of various modifications without departing from the spirit thereof or the scope of the appended claims.

What I claim is:

1. A stoker tuyère of the class described comprising a plate having its longitudinal sides inclined inwardly toward its rear end and having the outer side of its rear end portion curved, the underside of the plate having a depending marginal rib having the underside of its outer marginal portion substantially horizontal and the remaining portion thereof inclined transversely inwardly and upwardly to substantially the underside of the body of the plate, the underside of said rib being corrugated to provide a plurality of relatively long and narrow air passages extending substantially completely across said rib and having their outer end portions arranged substantially perpendicu-

lar to the adjacent portions of the outer side of the rib, and having their inner end portions directed forwardly, the air passages at the rear end of the rib being arranged substantially radially, and the air passages in the longitudinal portions of the rib being curved inwardly and forwardly. 40

2. A stoker tuyère structure of the class described comprising a plurality of tuyère blocks arranged one upon the other with the rear end of each tuyère block projecting a distance beyond the adjacent overlying block, each tuyère block comprising a plate having the rear portion of its longitudinal sides inclined inwardly toward its rear end, and with the outer side of its rear end portion curved, the underside of said rear portion of the plate having a depending marginal rib having the underside of its outer marginal portion substantially horizontal, the underside of said rib having a plurality of relatively narrow air passages extending transversely thereof and arranged in close proximity, the top side of each plate having a flattened portion of substantially the size and shape of the flat underside of the rib of the overlying plate and upon which the rib rests, and the top surface of the rear end portion of each plate having a raised portion inclined upwardly and rearwardly from a point adjacent to the extreme rear end of the overlying plate. 60

EDWIN LUNDGREN.
